CONVEYOR TRACK SWITCH

Frank J. Henderson, Detroit, Mich., assignor to Jervis B. Webb Company, Detroit, Mich., a corporation of Michigan

Application July 14, 1953, Serial No. 367,903

5 Claims. (Cl. 104—102)

This invention relates to a switch construction particularly designed for use with a trackway of the type formed by a pair of horizontally spaced rails. Trackways of this type are frequently employed in conveyor systems where the pair of spaced rails support the wheels of a trolley bracket which has a projecting portion extending between the space separating the rails. Usually, the projecting portion of the trolley bracket is equipped with some guiding means, such as rollers mounted on vertical axes, which coact with the vertical edges or flanges of the pair of rails to center the trolley to guide and reduce the friction during turns or in traversing curved portions of the trackway. In many installations, trolleys are propelled along a trackway of this type either by a separate driving conveyor, by hand, by gravity or by various forms of intermittent motion devices; and in systems, by combinations of these types of propulsion. Consequently, the trackway supporting the trolleys can be laid out to include main and branch lines, with selectively operable switches for directing the trolley in the desired path from one line to another.

The present invention is directed to improvements in the construction of such switches, which, in the past, have conventionally comprised a short track section for each direction of travel, e. g., main and branch, these track sections being mounted on a framework for lateral movement so that in switching from main to branch line the framework is moved laterally to replace the main line section with the branch line section. This type of construction is cumbersome, heavy and expensive. It requires a full break in all the track rails involved, which necessitates accurate fitting of the rail sections in order to minimize the possibility of trolley wheels becoming lodged in the space at a break. These full breaks also lessen the stability of the trackway, particularly in overhead or suspended trackway systems, or at least require additional track supporting members to maintain stability.

The present switch construction employs a tongue as a moving member. This tongue operates in conjunction with two continuous rail sections—which diverge to form a switch point—and is suspended for transverse movement between the rail sections, the tongue having two converging edge surfaces each complementary to one of the rail sections. The tongue suspension means permit the edge portion of the tongue to overhang the suspension and perform both the supporting and guiding functions of the trackway.

Preferably, the tongue is simply suspended from a member movably carried by an overhead framework, which, in turn is spaced vertically from the tongue a distance sufficient to provide clearance with a trolley passing along the track section located beneath the framework. This vertical spacing of the tongue is preferably an adjustable one to simplify the problem of properly aligning the switch with the adjacent track members during installation.

Presently preferred embodiments of the invention are shown in the accompanying drawing for the main types of

2

switch points encountered in normal practice—these being a 90° junction, either right- or left-hand, a Y junction, and a three-way junction. In each case the junction illustrates a switch particularly designed for an overhead conveyor

5 installation of the type where the load carrying trolleys are supported on a separate trackway such as previously mentioned. These load carrying trolleys are propelled along a main line by an overhead conveyor construction acting as a drive line. The switch construction permits 10 these load carrying trolleys to be diverted from the main line onto branch lines, or permits the trolleys to be fed from branch lines back onto the main line for propulsion by the drive line conveyor.

The drawing comprises the following views:

15 Fig. 1, a plan view of a 90° type switch.

Fig. 2, an elevation of the construction taken transversely through the main line trackway in the direction of the arrows 2—2 on Fig. 1.

20 Fig. 3, a sectional elevation of the construction taken along the line 3—3 of Fig. 1, the fixed trackways being omitted from this view for the sake of clarity.

Fig. 4, a sectional elevation taken along the line 4—4 of Fig. 1, likewise omitting the fixed track section.

25 Fig. 5, a plan view of the switch construction arranged for a Y-type junction.

Fig. 6, a plan view of the switch construction arranged for a three-way junction.

The plan view of Fig. 1 shows the relationship between the switch, a main trackway 11, and a branch trackway 12, both trackways being shown in phantom. The elevation of Fig. 2 shows that a trackway is composed of left- and right-hand angle members 13 and 14, respectively, which along the main trackway 11, are suspended by hangers 15 from an overhead I-beam 16 which forms a track for conventional overhead conveyor trolleys 17. These trolleys are connected by a chain which is driven by suitable driving means not shown, and thus forms a means for propelling a load carrying trolley 19 which travels along the main trackway in the direction of the arrow 18 in Fig. 1, assuming that the switch is positioned at the entrance end of a branch line.

At the switch point, the right-hand track angle 14 diverges from the main trackway in a curved path and 45 becomes a track member of a branch trackway. The left-hand track angle 13 continues through the switch point, unbroken. Beyond the switch point a track angle member 14a picks up the right-hand side of the main trackway, and a track angle member 13a picks up the left-hand side 50 of the branch trackway.

The switch construction of the invention employed at the switch point so formed consists in a simple framework located above the level of the trackways and comprising a pair of side frame members 20 and 21 (Fig. 4) interconnected at one end by an angle member 22 (Figs. 2 and 3), and by an intermediate transverse member 23 which consists in a piece of bar stock connected to the lower edges of the side frame members 20 and 21. The facing surfaces of the side frames are provided with longitudinally extending grooves or ways 24 which slidably support a plate 25.

Suspended from the plate 25 is a tongue member 26, the suspending means comprising three vertically extending rods 27. Each of these rods is secured to the tongue member 26 by being inserted within a hole 28 formed in the tongue member and welded in position. Bracing plates or gussets 29 extend between each pair of the rods 27 and are welded to the rods and to the surface of the tongue member to provide greater rigidity. 70 The upper end of each rod 27 is provided with a threaded portion 30, and passes through a hole 31 in the surface of the plate 25, the plate being secured to each post

between a pair of nuts 32 carried by the threaded portion thereof. This type of construction for connecting the tongue to the plate 25 is employed so as to afford some means for adjusting the relative vertical position between tongue member and its supporting plate 25. The three-point suspension afforded by the rods 27, in combination with the variable-length connection, affords adjustable relative positioning between plate and tongue member in all directions so that the tongue member can be correctly leveled with the adjacent track members after the switch assembly has been installed.

An air cylinder 35 is illustrated as a means for controlling the position of the switch, though hand operation is frequently employed in lieu thereof. This air cylinder has a clevis 36 on its rod 37 connected to a vertically extending post 38 by a pin 39. The post 38 is fixed to the upper surface of the supporting plate 25. The other end of the air cylinder is also provided with a clevis 40 which is secured to the horizontal flange 41 of the end frame member 22 by a pin 42.

Since many suitable types of valves for controlling the operation of the air cylinder 35 are commercially available, no particular type is shown. Fig. 1, however, does illustrate the fact that limit switches commonly employed for controlling such valves may be conveniently mounted above the main supporting plate 25 of the switch assembly. Two limit switches are indicated in phantom at 45 and 46 in this view, these being suitably carried by the fixed supporting structure so as to be actuated by a vertical member 47 secured to the upper surface of the plate 25. The valve controlled by these limit switches can be conveniently mounted on the supporting base 48 carried by the end frame member 22.

Fig. 1 shows the switch with the tongue member 26 in throw or branch line position. The tongue member 26 is seen to be generally triangular in shape. The hypotenuse 50 of this triangular shape is curved to correspond to the path of the branch line 12, and the vertical surface 50a (Fig. 4) forms a lateral guide for a trolley following the diverging branch line path. This vertical surface 50a is spaced outwardly from or overhangs, the points of support of the rods 27 by such a distance that the overhanging portion of the tongue forms a horizontally extending track surface 50b. The extent of this track surface is generally indicated by the space between the vertical edge 50a and the arc 51 shown in phantom, which arc indicates the path of travel of the outer edge of the wheels of the trolleys traveling towards the branch trackway 12.

One leg of the triangular-shaped tongue member 26 similarly forms the vertical and horizontal portions of the main trackway passing through the switch point. Here, the phantom line 52 generally indicates the inner boundary of the horizontal track surface, as defined by the wheels of a trolley, and again this surface of the tongue 26 is in outwardly or overhanging relationship to the points of support provided by the vertical rods 27. The vertical edge 53 of this leg forms the lateral boundary of the main trackway.

The switch is moved to straight-line position by actuation of the air cylinder 35 to draw the sliding supporting plate 25 towards the right as the parts are viewed in the plan showing of Fig. 1. This movement is limited so that the edge 53 of the tongue member 26 properly fairs into the straight-line trackway 11, either by the engagement of the curved edge 50a with the right-hand track member 14, or, if necessary, by engagement of the end surface 55 of the supporting plate 25 with a stop 56 carried by the end frame member 22. This stop 56 is adjustable in position by reason of the threaded shank 57 and pair of lock nuts 58, engaging the end frame member 22, as shown best in Fig. 3.

The switch assembly preferably includes two mounting plates. One of these is the generally triangular-shaped plate 60 shown best in Figs. 1 and 2 which has

its upper horizontal edge secured to the undersurface of the side frame member 20 at the left or entrance side of the switch. This plate 60 is provided with a horizontally extending slotted hole 61 and has an outwardly projecting portion 62 adapted to engage the underside of the horizontal flange of the track member 14. The plate 60 is adapted to be secured to a conventional track hanger 15 which is provided with a vertically extending slotted hole 63. A bolt (not shown) can be employed to connect the mounting plate 60 with the hanger 15 through the slotted holes thus providing for relative adjustment of the position of the switch assembly.

The other mounting plate is a member 65 of generally rectangular configuration having its upper horizontal edge 66 secured to the underside of the left or exit side frame member 21. The lower portion of the plate 65 is provided with two projecting portions. One, 67, engages the undersurfaces of the main track member 14a. The other, 68, engages the undersurfaces of the branch track member 13a. Plate 65 is also provided with a horizontally extending slotted hole 69 which registers with a vertically extending slotted hole 70 formed in another conventional track hanger 15a, these slotted holes 69 and 70 also being adapted to receive a bolt for adjustably mounting the switch assembly.

Thus, the switch mounting plates register with the track surfaces involved and connect to conventional track hangers. The adjustment provided in these connections, together with the adjustable amounting of the switch tongue member 26 permits the switch assembly to be readily aligned with the track sections in the field. Registry of the mounting plates 60 and 65 with the respective track sections and the track hangers tends to prevent any misalignment of the switch occurring during service.

Preferably, the end frame member 22 of the switch is also supported by cooperating engagement with another conventional track supporting yoke member 72, which is not shown in detail, but which is a member having a configuration somewhat similar to the yokes 15 and 15a, but being of lesser vertical height due to the fact that no propelling conveyor is employed in conjunction with the particular branch line 12 shown.

Except for configuration, the Y junction shown in Fig. 5 is very similar to the construction previously described. A switch station is formed at the point of divergence between two track members 113 and 114, these track members preferably continuing through the switch station unbroken.

A switch tongue 126 is suspended between the track members on vertical posts 127, connected by nuts 132 to a plate 125 which is slidably carried in grooves 124 of a pair of side frame members 120 and 121. These members 120 and 121 are part of the switch framework, which is completed by an end member 122 and a pair of cross bars 145 and 146. A pair of adjustable stops 147 are carried by each of the cross bars 145 and 146 to limit sliding movement of the plate 125 by contact with either end thereof.

Movement of the plate 125 and switch tongue 126 is shown as controlled by an actuating cylinder 135, having one end fixed to the frame end member 122 by a connecting pin 142 and its piston rod provided with a clevis 136 which is connected by a pin 139 to a post 138 attached to the upper surface of the plate 125.

The switch tongue 126 has track portions disposed outwardly of the points of connection of the vertical posts 127, which portions form continuations of either of the track members 113 or 114 depending upon the position of the tongue. In the position shown, the switch tongue connects the track 114 with a track section 114a in the upper left corner of the view; whereas, when the switch is thrown to its other position, by operation of the actuating cylinder 135, the end of the plate 125 contacts the stops carried by the cross bar 145 and the switch tongue provides a track portion for connecting the track

member 113 with the member 113a in the upper right corner of the view.

The three-way junction of Fig. 6 consists essentially in a pair of switch assemblies. Switch units of the type shown in Figs. 1 to 4 will ordinarily be manufactured in both left- and right-hand models. The construction shown in Fig. 6 combines standard left- and right-hand units to form a three-way junction so that a specialized assembly is not required for this purpose.

For convenience in describing the three-way junction arrangement, the entrance point of the junction will be assumed to be defined by the place of divergence between the members 213 and 214 of a trackway. Track member 213 curves to the left from the entrance point, while track 214 curves to the right, with the left and right trackways being taken up beyond the junction by track members 214a and 213a, respectively.

A left-hand switch assembly is employed for establishing a trolley wheel supporting surface between track member 214 at the entrance to the junction and track member 214a. This switch assembly includes a switch tongue 26L suspended by vertical posts 27 from a plate 25, slidably supported between side frames 20 and 21. These side frames are connected by an end frame member 22 and a cross member 23.

Connection between the track member 213 entering the junction and 213a leaving the junction to the right is established by a right-hand switch assembly including a switch tongue 26R and corresponding members for supporting it as indicated by the similar reference numerals applied to such members.

A through trackway extends from the junction and is defined by track members 203 and 204, with the tongue 26L of the left-hand switch assembly serving to establish a connecting track surface between track members 213 and 203 and the switch tongue 26R of the right-hand switch assembly serving to connect track members 214 and 204.

Actuating cylinders 35L and 35R are provided to control the position of the sliding plates supporting the left- and right-hand switch tongue members, respectively, these actuating cylinders each being connected between a post 38 carried by the sliding plate and the end member 22 of the fixed frame in the manner previously described.

The entire switch unit is shown in position to establish a connection between the trackway 213—214 and the left-hand trackway 213—214a. Straight-through operation between the trackways 213—214 and 203—204 is obtained by actuation of the cylinder 35L of the left-hand switch assembly to move the sliding plate thereof into contact with stops 56L and producing a separation between the left- and right-hand switch tongues along the line 205. This will be referred to as the "through" position of the switch unit.

Right-hand position, where a connection is established between the trackways 213—214 and 213a—214, is obtained by the actuation of both cylinders 35L and 35R from the position shown, the limit of movement again being defined by the left-hand stops 56L. If the switch is in through position, right-hand position is of course obtained by actuation of the cylinder 35R to move its associated sliding plate out of contact with the adjustable stops 56R, this movement continuing until contact between the switch tongue members 26L and 26R is re-established along the line 205, which is then displaced to the left from the position shown to form a continuation of the vertical guide surface of track member 203 and to lie tangent to the vertical guide surface of track member 213 at the entrance end of the switch.

Figs. 5 and 6 have been included mainly to illustrate the flexible nature of the switch construction of the invention and the relative ease with which it can be adapted to interconnect trackways at junctions of various types and configuration. For example, the construction of Fig. 5 is essentially the same as that of Figs. 1 to 4. The same

basic component parts are employed in each, with the difference in configuration of the junction being taken care of mainly by a change in the configuration of the switch tongue. The three-way construction of Fig. 6 is thought to offer a very convincing demonstration of the comparative simplicity between the construction of the invention and switch constructions heretofore employed for use with similar types of trackways. Such former constructions would commonly employ three, separate suspended sets of track sections, one left-hand, one straight-through, and one right-hand. These sections are mounted for lateral movement in unison to be selectively registered with their respective stationary trackways. Consequently a great range of movement is required, and the resulting construction is extremely heavy, cumbersome and expensive in comparison to the construction obtainable by the employment of the invention.

Any modifications to the construction shown included within the scope of the following claims, are to be considered as part of the present invention.

I claim:

1. A track switch construction for use with an overhead trackway of the type having spaced horizontal rails and vertical guide flanges for supporting a wheeled trolley, comprising a switch frame, a switch tongue having a pair of diverging, generally vertical guide surfaces each adapted to form a continuation of a vertical guide surface of said trackway and having wheel-supporting portions alongside the said vertical guide surfaces thereof, a reciprocable supporting member carried by said switch frame, and means suspending said switch tongue from said supporting member in spaced relation therewith for clearance between a trolley passing over said switch tongue and said switch frame, said suspending means being connected to said switch tongue within the area bounded by the wheel-supporting portions thereof for clearance between a trolley passing over said switch tongue and said suspending means.

2. A track switch construction as set forth in claim 1 further characterized by said suspending means including at least two vertically adjustable points of connection between said tongue member and said supporting member for adjustment of the horizontal attitude of said tongue member for alignment with said trackway.

3. A track switch according to claim 1 further characterized by said suspending means comprising a plurality of separate suspending members each carrying vertically adjustable connecting means, and brace members rigidly interconnecting said suspending members below the level of said connecting means.

4. A track switch construction for use with trackways of the type formed by a pair of rail members laterally spaced to provide a guide slot therebetween comprising a pair of switch tongues each having a pair of intersecting vertical surfaces adapted to form continuations of the side walls of said guide slot and horizontal wheel-supporting areas bordering said vertical surfaces, a framework, means for mounting each of said switch tongues on said framework for independent movement transversely of said trackway, said switch tongues being relatively positioned on said framework so that a vertical surface of one tongue extends substantially parallel and in confronting relation to a vertical surface of the other tongue, said mounting means including means for independently moving said switch tongues from positions where said parallel vertical surfaces thereof are adjacent to a position where said parallel vertical surfaces are separated by the width of said guide slot thereby forming a trackway between the parallel vertical surfaces of said switch tongues.

5. A track switch construction for use with trackways of the type formed by a pair of rail members having trolley wheel-supporting surfaces laterally spaced to provide a guide slot therebetween, comprising a supporting

member, means mounting said supporting member for movement generally transversely of said trackways, a tongue member having intersecting vertical surfaces each adapted to form a continuation of a vertical surface of said guide slot in each position of the switch, said tongue member also having horizontal wheel-supporting surfaces extending inwardly from said vertical surfaces thereof, means fixedly connecting and suspending said tongue member from said supporting member for movement therewith, said connecting means being secured to said tongue member within the area bounded by the horizontal rail-supporting surfaces thereof for clearance between a trolley passing over said switch tongue and said connecting and suspending means.
